UNITED STATES PATENT OFFICE.

ROBERT S. BOWEN, OF BOSTON, MASSACHUSETTS.

DESIGN FOR A PIANO-TOP.

SPECIFICATION forming part of Design No. 27,765, dated October 19, 1897.

Application filed September 10, 1897. Serial No. 651,257. Term of patent 14 years.

To all whom it may concern:

Be it known that I, ROBERT S. BOWEN, a citizen of the United States, residing at Boston, in the county of Suffolk and State of Massachusetts, have invented and produced a new and original Design for Piano-Tops, of which the following is a specification, reference being had therein to the accompanying drawings.

10 In the drawings, Figure 1 is a plan of a piano-top embodying my design, and Fig. 2 is a vertical section on the line 2 2 of Fig. 1.

The edge contour of the top is constituted of the long straight line A at the front of the instrument, the short straight line B and the longer straight line C extending back from the opposite ends of line A, the short curved lines D E, each of right-hand curvature and proceeding leftward and rearward from the rear extremities of lines B and C, the long straight line F extending diagonally backward and to the right from the rear extremity

of the curve D, and the long curved line G extending from the rear extremity of the curve E through about a semicircle and joining with 25 the rear ends of the lines F and E.

The design is characterized in particular by the feature that the line H, on which the front portion of the top is divided from the rear portion thereof, is extended across at right angles 30 to the edge F, so that when such front portion is folded back upon the rear portion the left-hand edges of both portions correspond in position, one overlying without overlapping the other.

35 What I claim is—

The design for a piano-top substantially as shown and described.

In testimony whereof I affix my signature in presence of two witnesses.

ROBERT S. BOWEN.
